UNITED STATES PATENT OFFICE

PER ANDERSSON KOURTZMAN, OF VARTAN, SWEDEN

ALARM APPARATUS FOR SPEEDOMETERS FOR VEHICLES

Original application filed January 31, 1929, Serial No. 336,364, and in Sweden February 8, 1928. Divided and this application filed April 1, 1930. Serial No. 440,830.

The present invention relates to an alarm apparatus for speedometers for vehicles. The characteristics of the invention consist in the combination of a rotating disc or wheel receiving its rotation from the movement of the vehicle, two diametrically opposed weights located in radial guides on the wheel and slidable in the same and provided with a pin, which is adapted to cooperate with a hammer for sounding a bell, and two springs located in said guides and each effective to oppose the tendency of one of said weights to move towards the periphery of the wheel under centrifugal force.

This application is a division of applicant's co-pending application, Serial No. 336,364, filed January 31st, 1929.

On the accompanying drawings is shown only by way of example the present invention applied to a speedometer which has a diagram cylinder provided with an adjustable diagram cord, a signal device and a counting mechanism. Fig. 1 shows the speedometer in side elevation. Fig. 2 is a vertical sectional view of the upper portion of the speedometer housing and showing the alarm apparatus in side elevation. Fig. 3 is a sectional plan view of the speedometer illustrating the relative positions of the mechanism at the interior thereof.

In the example shown in the drawings, the alarm apparatus is mounted in the upper part of a speedometer housing 10 and is operated from a shaft 24 forming part of a centrifugal device which is used for shifting the position of a diagram cord 12, as fully described in my said copending application.

In the upper part of the speedometer housing, a gear wheel 53 is mounted for rotation, said wheel being in mesh with a pinion 54, which in turn meshes with a similar pinion secured on the shaft 24, whereby rotary motion is transmitted to the wheel 53 from the shaft 24. The wheel 53 is provided at its underside with a pair of oppositely disposed guides 53^a extending diametrically of the gear wheel, and mounted in said guides at opposite sides of the axis of rotation of the gear wheel are a pair of weights 55 said weights being slidable radially of the gear

under the centrifugal force produced by rotation of the gear. A pair of springs 56 disposed between the outer ends of the weights and the outer ends of the guides serve to maintain the weights normally in retracted position and to resist outward movement of the weights. One of the weights carries at its outer end a pin 57, which pin will project beyond the periphery of the gear wheel when the latter is rotated beyond a predetermined speed and will contact with a pivoted bell hammer 58 once for each revolution of the gear wheel 53, thereby causing the hammer to swing on its pivot against the tension of a spring 59. As soon as the said pin has passed out of contact with the hammer, the latter is swung in the opposite direction by the tension of its spring so as to strike a bell 60 disposed in the path of said hammer.

In addition to the audible signaling device above described, the speedometer includes a visible signal for indicating when a predetermined speed limit has been exceeded, which is fully described in my said copending application, and since it does not constitute an essential feature of the present application, it is believed that a general reference thereto will be sufficient herein. In Fig. 3, the signal member 40 is carried at the end of an arm 37 of a double-armed lever pivoted on a pin 38, the lever being movable axially of said pin against the action of a spring 47. The other arm 39 of said double-armed lever lies in the path of a projection 41 carried on a wheel 17 secured to a shaft on which are mounted a pair of pulleys 18 by means of which rotary motion proportionate to the speed of rotation of the shaft 24 is transmitted to the wheel 17. By this means the lever 39 is actuated to raise the signaling member 40 so that it will be visible through the opening 71 in the speedometer housing, as shown in Fig. 1. The arms 37 and 39 are articulated together and maintained in operative relation by a spring 51, whereby the arm is cushioned so as to prevent damage in case of excessive speed. The speed recording mechanism is indicated at 46 in Fig. 3, and clamping means for securing the speedometer on a suitable support is indicated at 69, 70 in Fig. 1. None of these fea-

tures, however, are essential to the present invention.

Instead of being operated by the shaft 24 the alarm apparatus may be operated by some other movable part of the speedometer. The alarm apparatus may, if desired, be mounted in some part of the speedometer casing other than in the upper part. For instance, it may be mounted in the lower part of the speedometer and be operated by some other shaft which receives its rotation from the movement of the vehicle.

In short the separate parts of the alarm apparatus shown may of course be varied in many ways, provided only the characteristics of the invention are retained. The speedometer can be used on many different kinds of vehicles, for example motor cars, locomotives etc.

It is believed that the operation of the device will be apparent from the foregoing. Whenever the gear 53 is rotated at sufficient speed to cause the weights 55 to move outward against the tension of the springs 56, the pin 57 carried by one of said weights will contact with the beveled portion of the hammer shown clearly in Fig. 3, and will trip said hammer or cause it to move away from the bell 60. As soon as the pin has passed beyond said beveled portion, however, the hammer will be returned with a quick motion so as to strike the edge of the bell, thus giving an audible signal that the speed of the vehicle has passed a predetermined limit of safety.

This striking of the bell will be repeated for each rotation of the wheel 53 as long as the speed of the vehicle remains above the safety limit.

What I claim is:—

In a speedometer for vehicles, an alarm apparatus comprising a rotatable member geared for receiving motion at a speed proportionate to the speed of the vehicle, a pair of counterbalancing weights mounted in said member for slideable movement radially thereof under centrifugal force, springs opposing outward movement of said weights, a pin carried by one of said weights and adapted to project beyond the periphery of said rotatable member under the centrifugal movement of said weight, and a signaling device disposed in the path of said pin and adapted to be actuated thereby to produce an audible signal.

In testimony whereof I have signed my name to this specification.

PER ANDERSSON KOURTZMAN.
